UNITED STATES PATENT OFFICE.

JOHN D. PIERCE, OF CHICAGO, ILLINOIS, ASSIGNOR TO ALLMETAL WEATHER STRIP COMPANY, OF CHICAGO, ILLINOIS, A CORPORATION OF ILLINOIS.

STRIP-FORMING MACHINE.

1,201,757.

Specification of Letters Patent.

Patented Oct. 17, 1916.

Application filed February 25, 1915. Serial No. 10,567.

To all whom it may concern:

Be it known that I, JOHN D. PIERCE, a citizen of the United States, resident of Chicago, in the county of Cook and State of Illinois, have invented certain new and useful Improvements in Strip-Forming Machines; and I do hereby declare that the following is a full, clear, and exact description thereof, reference being had to the accompanying drawings, and to the letters of reference marked thereon, which form a part of this specification.

This invention relates to improvements in strip-forming machines and consists of the matters hereinafter described and more particularly pointed out in the appended claims.

The invention as shown herein is intended more especially for the formation of weather strips for windows and doors and includes various novel features whereby a machine may be provided for forming strips of various widths, for reeling said strips as they are formed, for measuring and registering the number of feet in each reel taken from the forming rolls and for inspecting and adjusting any irregularities in the strips as they are fed to the forming rolls.

The various advantages of my improved machine will appear more clearly as I proceed with my specification.

In the drawings: Figure 1 is a view representing a side elevation of a machine containing my novel improvements. Fig. 2 is a top plan view of the same. Fig. 3 is a view representing on an enlarged scale a vertical section through Fig. 1 in a plane indicated by the line 3—3 of Fig. 1. Fig. 4 is a view representing a partial end elevation of Fig. 3. Fig. 5 is a view representing a section 40 through Fig. 3 in a plane indicated by the line 5—5 thereof. Fig. 6 is a perspective view of a part of the formed strip, in this case a weather strip. Fig. 7 is a diagrammatic sectional view indicating the application of a weather strip to a door.

Referring now to that embodiment of my invention illustrated in the drawings:—10 indicates a bench or support for my improved machine. The machine has a frame 11 which rests upon and is securely attached to upright posts 12—12—12 which rest upon and are secured to the top of the bench 10. The frame 11 consists of parallel, longitudinally extending, laterally spaced bars 11^a—11^a arranged edgewise and of a longi-

tudinally extending board or table 13 resting upon and secured to the top edges of said bars 11^a. The board or table 13 terminates short of the rear ends of said bars, 11^a, which are attached together and held in spaced relation beyond said table by means of cross bars 14.

In the space between the side bars 11^a—11^a left uncovered by the table 13, are located a plurality of short, laterally spaced, longitudinally extending, parallel bars 15, which, together with said side bars, provide bearing supports for the rolls of strips that are to be operated upon by the machine to produce the formed strips. In the side bars 11^a and 70 in the short bars 15 are formed upright, associated, open bearing notches 16—17, there being associated notches 16—16—17—17 in each of a pair of adjacent bars and as illustrated in the present instance the notches 17 75 are spaced longitudinally a short distance to the rear of the notches 16.

18 indicates the rolls which are mounted on short stub shafts 19 and the notches are made of sufficient width to loosely receive 80 said shafts 19. The notches 16 are made of comparatively greater depth than the notches 17 for a purpose presently to be described.

The spaces 21—22—23—24 between the bars (there being four of such spaces in the 85 embodiment of the invention shown herein) are made of various widths and each space is sufficiently wide to accommodate a strip of a certain width.

On the table 13 there are fixed a plurality 90 of pegs 25 which are arranged in longitudinal rows and are spaced laterally to correspond with the different widths of strips and of the several spaces defined by the bars 11^a and 15. These pegs act to guide the 95 strips from the several rolls over the table.

26 indicates a bar adapted to fit between any two of the rows of pegs. 27 indicates laterally extending pins fixed at or near the ends of said bar for engagement with pegs at opposite ends of the table to prevent the longitudinal movement of the bar 26. Said bar is flat on the bottom and is provided with bottom edges 26^a—26^a which extend parallel to the longitudinal axis of the bar. As the strip from a roll is fed over the table 13, the bar 26 rests upon said strip and acts to hold the strip down on the table and prevent it from buckling. At the same time the operator is enabled by reason of 110

the parallel bottom edges 26^a—26^a to determine whether or not the strip is distorted to one side or the other. Transversely arranged guide rolls 13^a, 13^b are mounted at the end of the table 13 in brackets 13^c to direct the strips from the rolls over the table and under the bar 26.

The forming rolls are mounted on a standard 28 fixed to the top of the bench 10. Said forming rolls comprise a plurality of laterally spaced driven rolls 30—31—32—33 (four as shown in the present embodiment of the invention) fixed on a horizontal shaft 34 journaled in said standard and a plurality of associated friction rolls 30^a—31^a—32^a—33^a rotatively mounted on a shaft 35 spaced from (in this case above) the shaft 34. A bearing plate 36 spaced from the bracket 28 and secured to and rising from a horizontal extension 28^a thereof, provides a bearing for the ends of the shafts 34—35 that are distant from the bearing said shafts have in the bracket 28.

The forming rolls 30 to 33 and the corresponding friction rolls 30^a to 33^a are made of different widths to correspond with the different widths to be rolled by the machine.

The friction rolls 30^a to 33^a are separated by means of spacing disks 37 which extend down into the spaces between the peripheries of the forming rolls 30 to 33 and thus provide guiding flanges to retain the strips to be formed in the spaces between the several forming rolls and their associated friction rolls. The shaft 35 on which the friction rolls and spacing disks 37 are mounted, is provided with eccentric end bearing parts 38—38 and one end of said shaft has a squared head 39 to which a wrench or crank 40 may be applied to rotate said shaft about its eccentric end bearing parts so that the space between the peripheries of the forming rolls and their associated friction rolls may be varied or adjusted. The shaft 34 is likewise provided with a squared end 34^a for the attachment of a crank so that said shaft may be rotated to impart rotative movement to the forming rolls and their associated friction rolls.

The several forming rolls are made of such diameter that their peripheral length will equal one or more lineal units so that each rotation thereof will determine the number of units in the length of strip formed at each rotation of the forming rolls. As indicated in the drawings, the forming rolls have a circumferential length equal to two units, in this case, and on the plate 36 adjacent the end of the shaft 34 is placed a recording device 40 of any familiar or usual construction and having a star counting wheel 41. On the end forming wheel or other rotative part carried by the shaft 34 are fixed one or more pins 42 depending upon the lineal units carried by the length

of the circumference of the forming wheels (in this case two feet) arranged to engage and coact with the star wheel 41 of the counting device. Thus as the machine is operated, a lineal unit will be counted by the recording device for each lineal unit rolled or formed by the forming wheels of the machine.

A reel 44 is rotatively mounted below the set of forming wheels 30 to 33 (see Figs. 1 and 3). Said reel is arranged in such manner that it may be adjusted to bring it into line with any one of the forming wheels 30 to 33. As shown, said reel consists of a disk 45 to which are fixed a number of laterally extending, annularly arranged pins 46. The said disk is fixed on a shaft 47 which has bearing in an elongated sleeve 48 made integral with the standard 28. The shaft 47 is provided with a number of annular grooves 49 which are spaced apart distances corresponding to the spacing of the forming wheels 33. Near the outer end of the sleeve 48 is pivoted an arm or detent 50. Said detent engages within an annular slot 60 near the end of the bearing sleeve 48 and is adapted to engage in any one of the grooves 49 of the shaft 47. Thus the shaft 47, after the detent 50 is removed from engagement with any one of the slots 49, and after said detent is swung upwardly and outwardly as indicated in Fig. 5, may be adjusted to bring any of the other slots in line with the slot 60 in the bearing 48, whereupon the detent may be again swung into engagement with the said slot to lock the shaft in its new position. The pins 46 are arranged in a circle of a diameter substantially equal to the diameter of the forming rolls. One of the pins fixed to said disk, namely, the pin 46^a, is fixed in a radial slot 45^a of the disk and is furnished with a threaded end to receive a thumb nut 46^b by means of which it may be fixed in position. After a strip has been wound upon the reel, the thumb nut 46^b may be loosened and the pin 46^a moved toward the shaft 47. This will slightly lessen the length of the circumferential path about the pins 46 to such an extent that the roll of strip on the reel may be removed.

To drive the reel a pulley 51 is provided. Said pulley is feathered to the shaft 47 and is connected by means of a belt 52 to a pulley 53 fixed on the shaft 34. The pulley 51 is prevented from moving from its position in the plane of the pulley 53, when the shaft 47 is moved longitudinally in one direction or the other, by means of a bolt or pin 54 threaded through a lug 55 extending from the standard 28 and engaging within a groove 56 in the hub of the pulley 51. The pulley 51 is made preferably of smaller diameter than the pulley 53 so that the tendency is to drive the reel 45 at a more rapid

peripheral rate of speed than the forming rolls 30 to 33 are driven, with the result that the strip wound on the reel is always taut and any slip required is provided between 5 the belt 52 and the pulley 51. In starting the machine a sufficient length of the strip is drawn through the forming rolls to reach one of the pins of the reel, whereupon it is hooked upon said pin and thereafter the reel 10 will wind the strip upon itself as the machine is operated.

The machine shown herein is particularly designed for forming weather strips which consist of parallel narrow marginal parts 15 70—71 and an intermediate connecting web 72 which is inclined to said marginal parts. In the use of such strips, one marginal part, namely, the part 70, is used as the nailing edge for attachment to the jamb 73 of the 20 doorway or window opening, as indicated in Fig. 7, while the other part constitutes the free edge and is adapted to be engaged by the edge of the door or window (the door as shown in dotted lines in the drawings.)

25 In the case of a machine for forming weather strips such as that shown in the drawings, if the operator finds that the strip is favoring one side or the other of the bar 26, as it is fed over the table 13, he may cut 30 the strip and may remove the roll 18 from one of the deep notches 16 in which it is fed from the top of the roll and reverse and place it in one of the shallower notches 17 wherein it will be fed from the bottom of 35 the roll or vice versa. In this way the convex side of the strip may always be used to form the nailing edge of the strip so that when the strip is nailed in position on the door or window, the free edge will be 40 concave rather than convex and will thus necessarily be stretched in the process of attaching so that there will be no wave in the surface upon which the door or window closes.

I claim as my invention:

45 1. In a strip forming machine of the kind described, in combination with guiding means, forming rolls, friction rolls adapted to coat with said forming rolls, means for driving said forming rolls, said forming 50 rolls having a circumferential length which is equal to or a multiple of a lineal unit, a counting device associated with said forming rolls and a reel adapted to wind from said forming rolls, said counting device and 55 reel being operated from said forming rolls.

2. In a strip forming machine of the kind described, in combination with guiding means, forming rolls, friction rolls adapted to coat with said forming rolls, a reel 60 adapted to wind from said forming rolls, means for driving said forming rolls and reel, and means for adjusting said reel to

associate it with any one of said forming rolls.

3. In a strip forming machine of the kind 65 described, in combination with a plurality of forming rolls, friction rolls adapted to coat with said forming rolls, a reel for winding from said forming rolls, means for driving said forming rolls and reel, a shaft 70 on which said reel is mounted, and means for locking said shaft in several positions to bring said reel into line with any one of said forming rolls.

4. In a strip forming machine of the kind 75 described, in combination with forming rolls, friction rolls associated with said forming rolls and adapted to coat therewith, means for positively driving said forming rolls, a shaft belt-driven from said 80 forming rolls, a reel on said shaft, said shaft being capable of longitudinal movement to bring said reel in line with any one of said forming rolls, and locking means for locking said shaft in any one of the 85 several required positions.

5. In a strip forming machine of the kind described, in combination with a table over which the strips are adapted to be fed, coaxial forming rolls arranged tangential to 90 but below the top of said table, friction rolls coacting with said forming rolls, means for driving said forming rolls, and a removable gage bar adapted to be associated with any one of said forming rolls extending substantially the length of said table, and means for locking said gage bar against longitudinal movement as the strip is fed between it and the table.

6. In a strip forming machine of the kind 100 described, in combination with a table over which the strips are adapted to be fed, forming rolls arranged tangential to but below the top of said table, friction rolls coacting with said forming rolls, means for driving 105 said forming rolls, and a gage bar extending substantially the length of said table, means for locking said gage bar against longitudinal movement as the strip is fed between it and the table, and two sets of bearing notches for said feed rolls, one set being substantially deeper than the other set, and guide rolls arranged transverse of said table and adapted to feed said strips into the plane of the top surface of said table. 110 115

In testimony, that I claim the foregoing as my invention I affix my signature, in the presence of two witnesses, this 19th day of February, A. D. 1915.

JOHN D. PIERCE.
